(57) **CLAIM**

The ornamental design for a basketball game, as shown and described.

DESCRIPTION

FIG. 1 is a front view of the basketball game of the present design;

FIG. 2 is a rear view thereof;

FIG. 3 is left view thereof;

FIG. 4 is a right view thereof; and,

FIG. 5 is a perspective view thereof.

The portions of the drawings shown in broken lines represent environmental structure and form no part of the claimed design.

The word “SPIN-N-SHOOT” shown in the drawings is a registered trademark of Richard Schereck and forms part of the claimed design.
